United States Patent Office.

JULES MARIE DE LA RUË, OF NOGENT SUR MARNE, NEAR PARIS,
FRANCE.

Letters Patent No. 94,294, dated August 31, 1869; patented in France, December 14, 1868.

IMPROVEMENT IN FLOATING VELOCIPEDES.

The Schedule referred to in these Letters Patent and making part of the same.

To all whom it may concern:

Be it known that I, JULES MARIE DE LA RUË, of Nogent sur Marne, near Paris, in the Empire of France, have invented a nautical velocipede called "Tachypodoscaph;" and I do hereby declare that the following is a full, clear, and exact description thereof, which will enable others skilled in the art to make and use the same, reference being had to the accompanying drawings, forming part of this specification.

This invention relates to a locomotive nautical apparatus called "tachypodoscaph."

The principle of this apparatus rests on the use of a paddle-wheel, which is operated by treadles, and is arranged between two floats, as hereinafter described.

My tachypodoscaph is composed of two or more floats or boats, connected by cross-bars, and so set apart from one another as to allow the driving paddle-wheel to be fitted between them.

The paddle-wheels are set in motion by treadles, much like those in use for land velocipedes, and the apparatus is steered by a rudder, worked by a Vaucanson or other wheel.

The operator sits astride on a saddle fixed on a steel spring, while his feet rest on and actuate the treadle, his hands resting on the horizontal steering-bar.

The bar being connected with the helm will act upon the same with all desirable force and rapidity.

In case the equilibrium is accidentally lost, the action of the hands will quickly re-establish it by throwing the weight of the body to the opposite side.

I may provide my wheels with any number of paddles, but I prefer limiting them to twelve, so as to perfectly equalize the expense of force and the propelling-power, in other words, to reduce the strain and at the same time to secure the best working of the paddles, which, were they in greater number, would be too near to each other to answer their purpose in the most efficient manner.

The helm is what navigators call a "balance-helm."

The motion is transmitted by chains or ropes, actuated by a Vaucanson or other wheel, keyed to the tiller-rod.

In the accompanying drawings—

Figure 1 is a plan view of my nautical velocipede or tachypodoscaph;

Figure 2 is a longitudinal vertical section of the same on the line C D of fig. 1;

Figure 3 is a transverse section of the same apparatus in the line A B of fig. 2; and

Figure 4 is a view or cross elevation of the same apparatus.

Similar letters of reference indicate corresponding parts.

A A' A" A" are boats or floats, and made of any desirable material and form.

A wheel, H, or one or more, are provided with paddles in variable number.

H' are treadles, for the paddle-wheels.

K is the balance-helm, serving the double purposes of lever-arms and beam.

L L' are ropes, connecting the steering-bar and the helm K.

M M' is the steel sheet and spring, supporting the saddle or seat.

N is the India-rubber or other saddle or seat.

O O' are wrought-iron forks, admitting the connecting-rods of the treadles and the helm-rod.

P P' is the sheet-iron paddle-box; and

Q Q, cross-bars.

The seat or saddle may be single or double; that is to say, fitted for one person or two. It is movable, and made to slide on rails or otherwise.

Having thus described my invention,

I claim as new, and desire to secure by Letters Patent—

The herein-described nautical velocipede, consisting of the floats A A', united by the cross-bars g, the paddle-wheel H, enclosed in box O, spring supports M M', for the saddle N, the forks O O', balance-rudder K, and tiller-ropes L L', all combined, arranged, and constructed as shown.

DE LA RUË.
